2 SHEETS—SHEET 2.

UNITED STATES PATENT OFFICE.

JAMES F. O'CONNOR, OF ST. LOUIS, MISSOURI.

DUMPING-WAGON.

1,143,308.

Specification of Letters Patent. Patented June 15, 1915.

Application filed February 9, 1914. Serial No. 817,445.

To all whom it may concern:

Be it known that I, JAMES F. O'CONNOR, a citizen of the United States, and a resident of the city of St. Louis and State of Missouri, have invented a new and useful Improvement in Dumping-Wagons, of which the following is a specification.

My invention relates to dumping wagons and particularly to that type in which the dumping may be performed from the driver's seat.

The principal object of my invention is to provide a dumping wagon which can be used with equal facility for the transportation and dumping of dry and wet material and which can be easily loaded and dumped.

A further object of my invention is to attain certain advantages which will be more fully set forth hereinafter.

20 The invention consists in the parts, and in the arrangements and combinations of parts as will more fully appear hereinafter.

In the accompanying drawings, which form part of this specification, and in which like reference characters refer to like parts throughout the several views, Figure 1 is a plan view of a dumping wagon embodying my invention; Fig. 2 is a vertical longitudinal section of the wagon shown in Fig. 1; 30 Fig. 3 is a front end elevation, with certain parts removed; Fig. 4 is a vertical transverse section on the line 4—4 on Fig. 1, with the running gear removed; Fig. 5 is a fragmentary vertical longitudinal section on the line 5—5 on Fig. 3.

In the construction which I have shown as embodying my invention, a body frame is formed of an open rectangular frame comprising side pieces 1 and 2, a front piece 3 and a back piece 4. Secured in any suitable manner to this rectangular frame are side boards 5 and 6, a front board 7 and a rear board 8. The rectangular frame may be supported on any suitable form of running gear. Bolted to the upper face of the front piece 3 are two converging legs of a standard 9. Bolted to the upper face of the rear piece 4 are the converging legs of a standard 10. The standard 9 extends above the point 45 where the legs merge with one another, forming an upright portion 11. A wagon box 12 is formed of sheet metal and is substantially partly cylindrical in shape and segmental in cross-section. The rear end 13 of the wagon box 12 is straight, and the front end 14 is concaved outwardly from the

inside of the box. The ends 13 and 14 may be integral with the bottom and sides of the box 12, or they may be formed of separate pieces of sheet metal riveted or otherwise secured to said bottom and sides. Firmly secured to the ends 13 and 14 are trunnions 15 and 16 respectively. The trunnions are placed equidistant from the sides of the box 12, and at such a distance above the bottom 60 of the box that when the box is loaded it will be balanced about the axes of the trunnions. The trunnion 16 is mounted for free rotation in a circular hole 17 in the standard 9; and the trunnion 15 is similarly 65 mounted in a circular hole 18 in the standard 10. The trunnions 15 and 16 lie in a horizontal plane.

Pivoted by a pin 19 to the upper part of the upright portion 11 of the standard 9 is a 75 lever 20. The lever 20 in its normal position extends substantially horizontal and is provided at one end with an upwardly extending handle 21. The handle 21 is disposed at one side of the box 12 and in a position where it may be easily grasped by a driver from the seat 22. To the other end of the lever 20 is pivoted a link 23 which is pivotally secured to the end 14 of the box 12 at a point positioned to one side of the 80 trunnion 16.

Fastened to the inside face of the front board 7, at a point located on the same side of the standard 9 as the point of the pivotal connection of the link 23 and the end 14, is 85 an angle member or stop member 24. Fastened to the end 14 of the box 12 is a stop member 25 which engages with the lower face of the angle member 24 when the box 12 is in its normal upright position. On the 90 opposite side of the standard 9 is a second stop member 26 having its outer edge beveled. In a line with the stop member 26, when the box 12 is in its normal position, is fastened to the inside face of the front board 100 7 a bracket 27, having a horizontal bore. Slidably mounted in the bore of the bracket 27 is a catch 28, having at one end an integral beveled head 29 adapted to engage the upper surface of the stop member 26. An 105 expansion coil spring 30 between the front board 7 and the head 29 tends to hold the head 29 in engagement with the stop member 26. To the end of the catch 28 opposite the end having the head 29, is pivoted 110 an upwardly extending arm 31 integral with a rock shaft 32. The rock shaft 32 is piv-

totally mounted in strap bearings 33 and has an integral pedal 34.

Secured to the upper edges of the side boards 5 and 6 are boards 35 and 36 which 5 are inclined toward the center of the box 12 and have their inner edges close to the edges of the box. The frame structure of the wagon may be strengthened by straps or bands 37 fastened by nails or screws to the 10 front and rear boards 7 and 8 and extended over and fastened to the ends of the boards 35 and 36 and the side boards 5 and 6.

In the operation of the construction which I have shown and described, to dump a load 15 in the box 12, the driver, without leaving his seat, presses down upon the pedal 34. The depression of the pedal 34 withdraws the catch 28 and releases the box 12. The handle 21 is pulled, and by means of the link 23 20 the box 12 is swung on its trunnions 15 and 16 to the position shown in the dotted lines on Fig. 4. The stop member 25 engages the bottom face of the bracket 26 when the box 12 has reached its inverted position. To 25 place the box 12 back to its normal position, the driver pushes upon the handle 21 and rocks the box on its trunnions 15 and 16. As the box reaches its normal upright position, the beveled edge of the stop member 26 en- 30 gages the beveled portion of the head 29 of the catch 28 and pushes the catch back against the action of the spring 30. The stop member 25 engages with the angle mem- 35 ber 24 when the box 12 is in its normal up- right position and at this point the catch 28 engages the upper edge of the stop member 26 and holds the box 12 in its position.

The edges of the boards 35 and 36 lie close to the edges of the wagon box 12 so that the 40 wagon box may be easily loaded. The wagon box 12 is pivoted so as to be balanced, and this makes it possible to employ a simple lever for dumping the box. Also, on account of the wagon box 12 being balanced, 45 the load in it may be partly dumped without any additional effort on the part of the driver. The front end 14 of the box 12 is concaved to furnish room for the proper operation of the stop members 25 and 26 50 and the catch 28. In the normal upright position of the box 12, the stop member 25, by engaging the angle member 24, prevents rotation of the box on its trunnions 15 and 16 in one direction, and the head 29 of the catch 55 28, by engaging the stop member 26, prevents rotation of the box in the other direction. By this construction, the box 12 is held firmly in position and cannot rattle while its load is being transported.

50 The box 12 is made of sheet metal and can be used to transport wet materials, such as garbage and concrete, without leaking. The segmental cross-section of the box 12 permits it being partly dumped. Also the 55 shape of the wagon box 12 and the manner

in which it is mounted make it possible to completely invert the box, and make it certain that all of the material in the box will be dumped. When the load is dumped, it is dropped between the wheels of the wagon so 70 that it does not interfere with the movement of the empty wagon. The wagon box 12, when it is loaded, is balanced on its trunnions 15 and 16, and during the dumping movement the center of gravity of the load 75 remains in the line of the trunnions 15 and 16, and thus does not tend to overturn the wagon.

It is to be understood that the particular form of construction which I have shown 80 and described admits of considerable modification without departing from my invention. I do not wish, therefore, to be limited to the exact construction which I have shown and described. 85

What I claim is:

1. In a dumping wagon, a body frame, a wagon box composed of sheet metal and having a contour substantially segmental in cross-section, the front end of said box being 90 convex, trunnions fastened to each end face of said box, the axes of said trunnions passing through the center of gravity of said box when it is loaded, standards fastened to each end of said frame and pivotally supporting 95 said trunnions, a stop fixed to said frame at one side of said box, a stop member fixed to said box near one side thereof and adapted to engage said first mentioned stop when said box is in its normal up- 100 right position, a catch member mounted at the other side of said box and adapted to hold said box in its normal upright position, and means for inverting said box about its pivot axis to dump a load therein. 105

2. In a dumping wagon, a body frame, a wagon box formed of sheet metal and having a contour substantially segmental in cross-section, trunnions fastened to each end of said box, the axes of said trunnions passing approximately through the center of gravity of said box when it is loaded, a stop for preventing the rotation of said box on said trunnions from its normal upright position in one direction, a catch for preventing 115 rotation of said box from its normal upright position in the other direction, means for releasing said catch, a lever pivoted to said frame, and a link pivotally connected near one end to said lever and near the other end 120 to said box at one side of the axes of said trunnions, the other end of said lever extending to a place adjacent to the driver's seat, said link and said lever being operable to invert said box. 125

3. In a dumping wagon, a body frame, a wagon box formed of sheet metal and having a contour substantially segmental in cross-section, means for pivotally mounting said box on its longitudinal axis in said frame, 130

said frame having boards extending longitudinally thereof which slope outwardly and downwardly and have their upper longitudinal edges close to the longitudinal edges 5 of said box, when said box is in its normal upright position.

4. In a dumping wagon, an open rectangular body frame, a wagon box formed of sheet metal and having a contour substantially segmental in cross-section, a trunnion secured to each end face of said box, the axes 10 of said trunnions passing approximately through the center of gravity of said box when it is loaded, standards supported at each end of said frame and pivotally supporting said trunnions, a hand lever pivoted to one of said standards above the corresponding trunnion, a link pivotally connected at one end to said lever, and at the other end to said box below and at one side of the axes of 15 said trunnions.

5. In a dumping wagon, a body frame, a

wagon box pivoted in said frame, a stop member fixed to said frame, a stop secured to said box and engaging said stop member 25 to prevent rotation of said box from its normal upright position in one direction, a bracket secured to said frame, a second stop fastened to said box, a catch in said bracket engaging said second stop and preventing 30 rotation of said box from its normal upright position in the other direction, said first-named stop being arranged to engage said bracket automatically in the dumping position of said box, means for releasing said 35 catch and means for swinging said box on its pivot axis.

Signed at St. Louis, Missouri, this 6th day of February, 1914.
